UNITED STATES PATENT OFFICE.

WILLIAM H. WILDER, OF NORTHAMPTON, MASSACHUSETTS.

DESIGN FOR A LAMP-STOVE.

SPECIFICATION forming part of Design No. 23,810, dated November 13, 1894.

Application filed September 12, 1894. Serial No. 522,849. Term of patent 14 years.

To all whom it may concern:

Be it known that I, WILLIAM H. WILDER, a citizen of the United States, residing at Northampton, in the county of Hampshire and State of Massachusetts, have invented and produced a new and original Design for Lamp-Stoves, of which the following is a specification.

My design is shown in the accompanying drawing in which the figure represents a perspective view of the stove.

The leading feature of my design consists in a lamp stove having a base, a ring supported thereon, a dome surmounting the ring and a cap upon the dome.

In the accompanying drawing the body of

the stove is shown at A as supported upon feet a. A ring C rests upon the body portion and supported by this ring is the dome D provided with a series of perforations. Surmounting the dome is a cap piece b and above this cap is a water receptacle c.

What I claim is—

The design for a lamp stove herein shown and described.

In testimony whereof I affix my signature in presence of two witnesses.

WILLIAM H. WILDER.

Witnesses:

H. M. GATES,
E. A. THIRSELL.
